CLAIM

The ornamental design for a sole plate for a foot orthosis, as shown and described.

DESCRIPTION

FIG. 1 is a perspective view of a sole plate for a foot orthosis, showing my new design;

FIG. 2 is a top plan view thereof;

FIG. 3 is a left end elevational view thereof;

FIG. 4 is a side elevational view thereof, the opposite side elevational view being identical thereof;

FIG. 5 is a bottom plan view thereof; and

FIG. 6 is an enlarged fragmentary right end elevational view indicated by the line 6—6 in FIG. 3; and,

FIG. 7 is a right end elevational view thereof.
